HULL EXTRACTING CLEANER FEEDER

Jeffrey J. Wallace, Amite, La., assignor to Gullett
Gin Company, Amite, La.

Application April 2, 1934, Serial No. 718,729

3 Claims. (Cl. 19—37)

The invention forming the subject matter of this application relates to hull extracting cleaner feeder gins; and is in the nature of an improvement on the hull extracting unit disclosed in my 5 U. S. application, Ser. No. 670,565, filed May 11, 1933 for a Hull extracting unit.

The main object of the present invention is to improve the efficiency of machines of the type described in the aforesaid pending application by 10 substituting for the saw cylinder of such device, a cylinder covered with card clothing, the teeth of which are, of course, arranged much closer together than is possible with saws without materially increasing the weight of the cylinder, as 15 well as its cost.

Another object of the invention resides in discharging hulls from the machine throughout the length of the cylinder and on to a discharge screw conveyor, in order to avoid the injury inherent in 20 the usual method of spiraling hulls and cotton along the cylinder to a discharge outlet at one end of the cylinder. The old method of spiraling discharge, cuts and breaks the hulls and causes the shale from the hulls to get into the lint, thereby 25 injuring the lint; and in addition thereto, twists the fiber and otherwise injures the sample.

Other objects of the invention will appear as the detailed description thereof proceeds.

In the drawing:

30 Figure 1 is a central vertical section through a machine embodying the present invention; and Figure 2 is a fragmentary elevation of one end of the machine shown in Figure 1.

As shown in the drawing, the machine comprises a casing 1 having an inlet opening 2 at its upper end designed to receive cotton to be cleaned or hulled. Immediately below the inlet opening 2 a pair of feed rollers 3 and 4, rotatably mounted between the end walls of the casing 1, are employed to direct the cotton to be cleaned onto a cleaner drum 5. The cleaner drum 5 is mounted to rotate between the aforesaid end walls, and directs the cotton received from the feed rollers 3 and 4 through a passageway 6, controlled by a 40 valve plate 7, to the hull extracting part of the machine. When the valve plate 7 is closed, the cotton is directed by the cleaner drum 5 along a screen partition 8 to a second passageway 9 leading to a second cleaner drum 10 mounted rotatably at the outlet hood 11. A spout 12 pivotally connected to the hood 11 directs the cleaned cotton to the roll box of a cotton gin (not shown). 50

When the by-pass valve 7 is open, the cotton is directed to the hulling chamber 13 at the rear of the machine. Suitably secured to the rear

wall 14 of this chamber, are a series of off-set members 15, 16 and 17, generally inclined toward a drum 18 which is covered with card clothing. The drum 18 is rotatably mounted between the end walls of the casing and a deflector plate 19 depending from the framework of the screen partition 8 serves to direct the tufts of cotton adhering to the teeth of the card clothing downwardly against a brush 20 mounted to rotate between the end walls of the casing about an axis parallel to the axis of rotation of the drum 18. A screen partition 21 is arranged below the brush 20 and directs the cotton removed by said brush from the card roll 18 upwardly against the cleaning drum 10 at the outlet of the casing. Directly below the screen partition 21 there is detachably mounted a section 22 in which there is rotatably mounted a wiper 23, adapted to throw all dirt, sand and trash passing through the screen 21 into a trough 24 in which a spiral trash conveyor 25 20 is rotatably mounted.

The inclined member 16, as previously described, is inclined toward the periphery of the drum 18, to direct the hulky cotton against the drum 18. A valve plate 26, rotatably mounted at the lower 25 end of the inclined member 16, is angularly adjustable toward and from the periphery of the drum 18 to vary the extent of opening of the passageway 27 leading to a compartment 28 directly below the member 18. This valve plate 26 30 may be adjusted to hold the cotton, trash and hulls in the upper part of the machine for a longer or shorter interval of time, depending upon the amount of foreign material to be removed, as well as to provide an opening, the size 35 of which may be varied to suit the character of the hulls to be discharged.

The lower portion of the inclined member 17 is curved to form a trough 29 under a spiked roller 30 which is arranged below the drum 18, 40 and to one side of a diameter passing vertically through the axis of the drum. Directly above and to one side of the same diameter of the drum 18, there is rotatably mounted a stripper cylinder 31, having bars arranged to strip or 45 knock off hulls and trash which may adhere to the cotton drawn up by the teeth of the card roll 18. A stripper plate 32 is fixedly secured to the inner end of the screen partition 8 and is provided with teeth arranged to enter the spaces 50 between the rows of bars 33 on the stripper cylinder. This construction is quite similar to that of the corresponding elements disclosed in my aforesaid U. S. application.

The valve plate 26 is secured to a shaft 34, 55

one end of which is secured to a disk 35 (see Figure 2) rotatably mounted in a bearing 36 detachably secured to the end wall 37 of the casing 1. A link 38 is pivoted at one of its ends eccentrically to the disk 35. The other end of the link 38 is pivoted to one end of the lever 39 having a handle 40 at its other end. The lever 39 passes slidably through a slot formed in a stop plate 41 suitably secured to the flange 42 formed on the end wall 37 of the casing. The lower edge of the lever is provided with a series of notches 43 adapted to seat in one edge of the slot in the plate 41. There is nothing particularly novel in this lever adjusting mechanism. Any suitable means may be used to adjust the valve plate 26 within the chamber 13 to vary the passageway 27 leading to the chamber closed at its lower end by the spike roller 30.

The spike roller 30 rotates in a direction opposite to the direction of rotation of the drum 18, and is intended to discharge the hulls out of the machine throughout the entire length of the cylinder and onto the spiral conveyor 25. The shape of the trough 29 is such as to cause the hulls to be thrown up forcibly against the bottom of the drum 18, thereby causing any locks of cotton in the discharged material to impinge on and adhere to the card clothing of the drum 18. The hulls and other foreign matter fall by gravity from the drum directly on to the endless conveyor 25 and throughout its length.

This discharge mechanism increases the capacity of the gins over that obtainable by prior construction in which the cotton and hulls are spiraled past the lower portion of the cylinder to a discharge outlet at one end thereof. This old method sets up a congested condition in the discharge of hulls and causes the cotton to be fed unevenly to the cylinder, and thereby to pass out of the machine into the gin in greater quantities at one end than at the other, and also decreases its capacity. The cleaning capacity is also improved in the present machine since cotton is cleaned better when it is spread evenly over the screen.

While I have shown and described the preferred embodiment of my invention, it is to be understood that I do not limit myself to the precise construction herein disclosed and the right is reserved to all changes and modifications coming within the scope of the invention as defined in the appended claims.

What I claim is:

1. In a hull extracting cleaning feeder, a casting providing a huller chamber, a toothed roll rotatable in said chamber, means to direct cotton against one side of said roll, a knocker rotatable adjacent the lower side of said roll and in a direction opposite to that of said roll, said knocker comprising a cylinder having pins projecting from the surface thereof in annular parallel rows spaced apart lengthwise of the cylinder, a trough extending below said knocker

and shaped to direct cotton from said knocker upwardly and radially only against the lower side of said roll, and a trash conveyor located directly below said roll to receive throughout its length waste material falling by gravity from the material directed against said lower side by said knocker said trough being located as a whole at one side of a plane containing the axes of said roll and conveyor to permit material to fall freely by gravity, from the roll onto the conveyor throughout the lengths of said roll and conveyor.

2. In a hull extracting cleaning feeder, a casting providing a huller chamber a toothed roll rotatable in said chamber, means to direct cotton against one side of said roll, a knocker rotatable below said means adjacent the lower side of said roll and in a direction opposite to that of said roll, said knocker comprising a cylinder having pins projecting from the surface thereof in annular parallel rows spaced apart lengthwise of the cylinder, a trough extending below said knocker and shaped to direct cotton from said knocker upwardly and radially only against the lower side of said roll, a trash conveyor directly below said roll to receive throughout its length waste material falling by gravity from the material directed against said lower side by said knocker, the said means including a baffle angularly adjustable to vary the cross sectional area of the stream of cotton where it impinges against the side of said toothed roll above said knocker, and means for holding said baffle in adjusted position said trough being located as a whole at one side of a plane containing the axes of said roll and conveyor to permit material to fall freely by gravity, from the roll onto the conveyor throughout the lengths of said roll and conveyor.

3. In a hull extracting cleaning feeder, a casting providing a hulling chamber and a cleaning chamber, a toothed roll rotatably mounted in the hulling chamber, means in the hulling chamber for directing a stream of cotton against one side of said roll, and means on the other side of said roll for removing cotton therefrom and directing it to the cleaning chamber, a trough mounted in said hulling chamber below said roll, a knocker rotatable in said trough in a direction opposite to the direction of rotation of said roll to direct cotton upwardly and radially only against the lower side of said roll and throughout its entire length, said knocker comprising a cylinder having pins projecting from the surface thereof in annular parallel rows spaced apart lengthwise of the cylinder, and a trash conveyor directly below said roll, said trough being located as a whole at one side of a plane containing the axes of said roll and conveyor to permit material to fall freely by gravity from the roll on to the conveyor throughout the lengths of said roll and conveyor.

JEFFREY J. WALLACE.
